[57] ABSTRACT

An angular position selecting and controlling device for a rotary member enabling to easily and arbitrarily pre-select a plural number of angular stopping positions of a rotary member by operating a button, and also enabling, by operation of another button, to stop the rotary member reliably with minimum power consumption successively at angular positions pre-selected as mentioned above, said angular position selecting and controlling device comprising a plurality of pins movably fitted along the circumference of the rotary member, two controlling levers for making those pins project from and push into the surface of the rotary member, an electromagnet having an armature which is capable of locking the rotary member at a stopped position, a stop lever engageable with the above-mentioned pins, a locking lever being engaged with said stop lever and being capable of holding the above-mentioned armature at a position where said armature is attracted by the electro-magnet, a switch for starting the rotary member by operation of the above-mentioned button and at the same time for energizing the electromagnet, and a switch for continuing the rotary motion of the rotary member being closed by the armature when said armature is attracted by the electro-magnet.

**ANGULAR POSITION SELECTING AND
CONTROLLING DEVICE FOR A ROTARY
MEMBER**

BACKGROUND OF THE INVENTION

a. Field of the invention:

The present invention is concerned with a rotation controlling device of a body of rotation and more particularly, to an angular position selecting and controlling device for a rotary member which pre-select a plurality of angular positions of the rotary member and stop the rotary member at said angular positions in turn.

b. Description of the prior art:

An angular position selecting and controlling device for a rotary member can be applied to a wide range of machinery and apparatus. Especially, this kind of device can be suitably utilized as an automatic channel selecting and change-over device for a tuning circuit of an all-channel tuner for a television receiving set. For this kind of use, a patent is already applied for as U.S. Pat. application Ser. No. 202,745 filed Nov. 29, 1971, now U.S. Pat. No. 3,740,679. In the invention of the above-mentioned application, the rotary member is stopped by using an electro-magnetic device having an armature which can be engaged with said rotary member. Said electro-magnetic device is to be excited by a signal for starting the operation and de-energized by a signal for stopping. This kind of stopping device, however, has some drawbacks. First, as the electro-magnetic device is to be kept excited during rotary operation of the rotary member, a self-holding circuit for the power source is required for the electro-magnetic device. Secondly, power consumption is large as the electro-magnetic device is kept excited during operation of the rotary member. Thirdly, the stop signal of the rotary operation is to be taken out from the stopping position limiting members arranged on said rotary member. But, there occurs a delay or time lag in operation of the electro-magnetic device from the moment when the signal is taken out to the moment when the electro-magnetic device is deenergized by the signal and the armature engages with and stops the rotary member and moreover, said delay is unstable and it is difficult to keep the delay at a constant value. Consequently, it is difficult to stop said rotary member at the desired pre-determined position.

SUMMARY OF THE INVENTION

It is, therefore, a primary object of the present invention to provide an angular position selecting and controlling device for a rotary member for which said drawbacks are eliminated, i.e., when the electro-magnetic device is excited by the signal for starting rotary operation, said armature is mechanically locked at a position being disengaged from said rotary member so that said armature cannot stop said rotary member even if the electro-magnetic device is de-energized after that, besides, when stopping rotary motion of said rotary member, an angular positioning member arranged on said rotary member releases said locking mechanically and, at the same time as released, said rotary member is stopped by said armature.

It is another object of the present invention to provide an angular position selecting and controlling device for which a plurality of angular positions of the ro-

tary member can be pre-selected easily and reliably by push-button control.

Other objects, features and advantages of the present invention will be apparent from the following description of the preferred embodiments of the invention illustrated in the accompanying drawings.

BRIEF DESCRIPTION OF THE DRAWINGS

FIG. 1 shows an explanatory view of an embodiment 10 of the angular position selecting and controlling device according to the present invention;

FIG. 2 shows a sectional view along the line II-II in FIG. 1;

FIG. 3 shows a sectional view along the line III-III 15 in FIG. 1;

FIG. 4 shows a sectional view along the line IV-IV in FIG. 1;

FIG. 5 shows an explanatory view of a channel selecting mechanism which can be utilized in combination with the controlling device shown in FIG. 1 through FIG. 4;

FIG. 6 shows an electric connection diagram for the embodiment shown in FIG. 1 through FIG. 5;

FIG. 7 shows an explanatory view of another embodiment 25 of the setting and resetting mechanism for the angular position limiting members of the controlling device according to the present invention;

FIG. 8 shows a sectional view along the line VIII-VIII in FIG. 7; and

FIG. 9 shows an electric connection diagram showing another embodiment of the control circuit according to the present invention.

**DETAILED DESCRIPTION OF THE PREFERRED
EMBODIMENTS**

The present invention is described in the following according to the embodiments where the invention is applied to a tuning means of television receiving sets.

Referring to FIG. 1, numeral 1 designates a base plate which is suitably fixed to the body of the television receiving set not shown here. Numeral 2 designates a motor mounted to the base plate and having a rotary shaft to which a pinion 2a is integrally mounted. Numeral 3 designates a gear which meshes with said pinion 2a and to which pinion 3a is integrally mounted. Numeral 4 designates a gear meshing with said pinion 3a. Numerals 5 and 6 designate gears which are mutually connected in a manner like a friction clutch by the means not shown here and said gear 5 meshes with said gear 4. Numeral 7 designates a channel display block having a mechanism similar to the leaftype digital indication clocks of known art for which multiple leaves are mounted to a drum rotating corresponding to time and are turned over also corresponding to time, thus indicate time digitally by means of digits written on surfaces of said leaves. Numeral 8 designates said leaves two of which are shown here out of multiple leaves and other omitted here. Numeral 9 designates a drum to which multiple leaves 8 are mounted. Numeral 10 designates a gear mounted integrally with said drum 9 and meshing with said gear 6. Numeral 11 designates a leaf lock fixed to the base plate 1. Numeral 12 designates a channel selecting drum fixed to a shaft 13 which is rotatably supported by said base plate 1. To the drum 12, a gear 14 meshing with said gear 6 is mounted integrally.

As shown in detail in FIG. 1, holes h (h_1, h_2 through h_n), respectively corresponding with each channel of the total channel number n , and a hole h_0 for the reset position are provided along the circumference of the face of a channel selecting drum 12. Said holes are equally spaced by dividing the circumference by $n + 1$. Along the periphery of said drum 12, notches C (C_0, C_1, C_2 through C_n) for positioning and manual feed are formed in the number which corresponds to the number of said holes h ($n + 1$). Besides, at the middle of said periphery of the drum 12, an annular groove 12a with a depth reaching said holes h is formed as clearly shown in FIG. 2 and, moreover, a protuberance 12b is also formed on said periphery. Reference symbols P (P_0, P_1, P_2 through P_n) designate channel selecting pins respectively fitted in each of said holes h of said drum 12. (In FIG. 1, single circles represent, for convenience sake, pins projecting toward the rear side as seen in the figure and double circles represent pin projecting toward the front side.) As shown in FIG. 2, two annular grooves g_1 and g_2 are formed on the periphery of every pin. Numeral 15 designates a belt elastically fitted in the annular groove 12a of said drum 12.

Numeral 16 designates an electro-magnet (see FIG. 6) for stopping which is arranged at the position where a holding pin 16b attached to an armature 16a can engage in the notches C of said drum 12. Said armature 16a has a stepped portion 16c as shown in FIG. 3 and is biased by the spring 17 in the direction away from the iron core. Numeral 18 designates a stop lever having two arms 18a and 18b which is pivotably mounted to a shaft fixed to the base plate 1. Said arm 18a can be engaged with said selecting pins P when they are projecting toward the forward side in FIG. 1. Numeral 19 designates a locking lever having two arms 19a and 19b which is mounted to a shaft fixed to the base plate 1 and is biased counterclockwise by a spring 20. Said arm 19a is engaged with the arm 18b of said lever 18 while the tip of said arm 19b can be engaged with the armature 16a of said electro-magnet 16. Reference symbol SW₂ designates a normally-open type switch (see FIG. 6) which closes, when the armature 16a of said electro-magnet 16 is attracted, by engaging with said armature 16a. Reference symbol SW₃ designates a selector switch which is changed over by the arm 18b of said lever 18. Reference symbol SW₄ designates a normally-open type switch which closes by engaging with the protuberance of said drum 12. Numeral 21 designates a channel controlling lever slidably mounted to the base plate 1 and being biased leftward in FIG. 1 by the spring 22. Numeral 21a designates a button fixed to one end of said lever 21. Reference symbol SW₁ designates a normally-open type switch which closes by engaging with another end of said lever 21 when the lever 21 moves rightward in FIG. 1.

In FIGS. 1 and 4, numeral 23 designates a first controlling lever for feeding said drum 12 manually and for setting said channel selecting pins P. Numeral 24 designates a second controlling lever for resetting said pins P. Both levers 23 and 24 are supported by the base plate 1 and a post 25 mounted to said base plate and can be removed rightward and leftward in the figures. Numerals 23a and 24a represent buttons respectively fixed to levers 23 and 24. Said lever 24 has a stepped portion 24b and a slot 24c which engages with said post 25. Besides, pins 24d and 24e are fixed to said lever 24. Numeral 26 designates a spring fixed to the base plate

1 on one end and to said pin 24e on the other end. Said lever 23 has a stepped portion 23b similar to the stepped portion 24b of said lever 24. Numeral 27 designates a feed lever having slots 27a and 27b, a stepped portion 27c and a pin 27d fixed to said feed lever 27. To said slots 27a and 27b, pins 24d and 24e of said lever 24, are fitted thus, said lever 27 is movably mounted to said lever 24. Numeral 28 designates a spring stretched between said lever 24 and lever 27. Numeral 29 designates a feed pawl pivotably mounted to the pin 27d of said lever 27 and biased counterclockwise by the spring 30. The free end of said pawl 29 engages with the notches C of said drum 12. Numerals 31 and 32 respectively designate the setting lever and resetting lever for setting or resetting said channel selecting pins P which are pivotably mounted to shafts 33 and 34 fixed to the base plate 1 and are biased counterclockwise or clockwise by springs 35 or 36 stretched between said lever 31 or 32 and base plate 1.

20 Numerals 37 and 38 designate pin hammers which are respectively extending from said levers 31 and 32 and can be engaged with each end portion of the channel selecting pins P on said drum 12. Said lever 31 comes to its static position when the protuberance 31a is engaged with the stepped portion 23b of said first controlling lever 23 and a portion (not shown) of said lever 23 contacts the base plate 1. Said lever 32 comes to its static position when similarly provided protuberance 32a contacts said shaft 33. Besides, said protuberance 32a can be engaged with the stepped portion 24b of said second controlling lever 24.

FIG. 5 shows a tuning circuit change-over mechanism block which is mechanically independent of the channel selecting mechanism block shown in FIG. 1. Numeral 39 designates a base plate mounted to the television receiving set body which is not shown here. Numeral 40 designates a group of contacts of a switch mechanism fixed to said base plate 39. The common contact T₀ and individual contacts T₁, T₂ through T_m are connected to a (variable) resistance circuit group for imposing the tuning voltage, which corresponds to each channel, for example to the variable capacity elements in the tuning circuit not shown here. Numeral 41 designates a rotary shaft for changing over said switch mechanism 40 which is supported by a method not illustrated. Said shaft 41 carries ratchet teeth R with the number corresponding to said contacts and also carries a sliding contact piece not illustrated, which connects said common contact T₀ to individual contacts. Said shaft 41 is further provided with a spring not illustrated which biases said shaft 41 clockwise in FIG. 5 and is arranged so that it is stopped at a pre-determined reset position by a stopper not shown when said shaft 41 is free. Numeral 42 designates an electro-magnet for feed (see FIG. 6) fixed to said base plate 39. The armature 42a of said electro-magnet 42 is biased by a spring 43 in the direction away from the iron core and a pin 42b is fixed to the tip of said armature 42a. Numeral 44 designates a feed pawl which is rotatably mounted on said pin 42b. Said feed pawl is biased clockwise around said pin 42b by a spring not illustrated and is held, when it is free, at a pre-determined position (shown by a dotted line) by means of a stopper not shown here. Said pawl 44 can be engaged with said ratchet tooth R. When said electro-magnet 42 is de-energized after being excited, said pawl 44 engages with one of said ratchet teeth R by action of the spring 43 and changes the connection

by one pitch of said teeth R, that is, to the adjacent contact in the contact group T. Numeral 45 designates a fixed guide of said pawl 44. Numeral 46 designates an electro-magnet for resetting, an armature 46a of which is rotatably mounted to a shaft 47 fixed to said base plate 39 and is biased counterclockwise by a spring 48. The free end of said armature 46a forms a stopping pawl 46b which is engaged with a ratchet tooth R on said shaft 41 when said electromagnet 46 is not energized.

FIG. 6 shows electric connection which relates the channel selecting mechanism block shown in FIG. 1 and tuning circuit change-over mechanism block shown in FIG. 5. Reference symbols SW₁ through SW₄ respectively designate switches in the above-mentioned mechanisms. Numerals 16', 42' and 46' respectively represent coils of electro-magnets 16, 42 and 46. Reference symbols D₁ through D₃ designate diodes and reference symbol R represents a resistor. Reference symbol SW₅ represents a remote control switch which can be connected in parallel to the switch SW₁ as required. Reference symbols a and b designate change-over contact terminals of said switch SW₃ and reference symbol c represents the output terminal of the operation signal of the AFC circuit.

The operation of the embodiment of the present invention arranged as above is as described below.

The embodiment shown in FIG. 1 is in the condition that the channel "n-2" is selected and the following description refers to the case where the channel "1" is to be selected from the above condition. In the condition shown in FIG. 1, every switch is at the position shown in FIG. 6 and the motor 2 and electro-magnets 16, 42 and 46 are all in de-energized condition. When the button 21a of the channel controlling lever 21 is pushed in this condition, the switch SW₁ is closed, the circuit from the motor 2 to the switch SW₁ through the diode D₁ is formed as it is evident from FIG. 6 thus the motor 2 is started. At the same time, the circuit from the electro-magnet 16 to the switch SW₁ is also formed, and therefore, the electro-magnet 16 is energized, and its armature 16a is attracted and moves to the position shown by a dotted line. Consequently, the channel selecting drum 12 is disengaged from the holding pin 16b and begins to rotate as driving power from the motor 2 is transmitted to the gear 14 through gears 3, 4, 5 and 6. At that time, the feed pawl 29 is engaged with and then disengaged from notches C on the periphery of said drum 12. As said drum 12 rotates, the stop lever 18, which is turned counterclockwise (to the position shown by a full line) because its arm 18a is engaged with the pin P_{n-2} projecting to the front side as seen in FIG. 1, turns clockwise as it is disengaged from said pin P_{n-2} and moves to the position shown by a dotted line. This motion is caused by the force of the spring 20 applied to the locking lever 19 which is engaged with said lever 18. As said lever 18 moves, said lever 19 also moves to the position shown by a dotted line. Therefore, on this stage, the armature 16a is mechanically held in the attracted condition (position shown by dotted lines), as illustrated, even if the pushed button 21a is released, the switch SW₁ is opened and the current to the electro-magnet 16 is disconnected due to the fact that the arm 19b of said lever 19 has been put into the stepped portion 16c of said armature 16a (See FIG. 3).

On the other hand, the switch SW₂ is closed when said armature 16a is at the attracted position, the circuit from the motor 2 to the switch SW₂ is formed instead of the above-mentioned motor driving circuit even when the switch SW₁ is opened, thus the motor 2 and consequently the drum 12 keep on rotating. As the pin P_{n-1} at the position of the adjacent next channel "n-1" is not in the set position, the lever 18 is kept at the position illustrated by a dotted line and said drum 10 keeps on rotating without stopping at the selecting position of said channel "n-1". As the pin P_n at the position of the next channel "n" is in the set position, the arm 18a of the lever 18 is pushed up by said pin P_n as the drum 12 rotates and said lever 18 is turned counterclockwise. The armature 16a, which was mechanically held, turns clockwise to the position shown by a full line because the lever 19 turns clockwise according to counterclockwise turn of the lever 18 and its arm 19b releases the armature 16a. So, the holding pin 16b engages with the notch of the drum 12 and stops the drum 12. Thus, the channel "n" is selected. As gears 5 and 6 are coupled like a friction clutch, inertia of the motor 2 for which the power source is disconnected by opening of the switch SW₂ is absorbed by said friction clutch at that time and the drum 12 can be easily stopped instantaneously from the rotating condition.

On the other hand, by the above-mentioned operation, rotation of the gear 6 is also transmitted to the gear 10. Thus, the leaf 8 is turned over corresponding to the channel selecting position of said drum 12 and the channel number "n" is indicated in this case. When the button 21a is pushed again, in the above condition, to close the switch SW₁, an operation same as mentioned above is carried out and the drum 12 stops at the position where the lever 18 is turned counterclockwise by the pin P₁ which is set at the next position relative to rotation of the drum 12. Thus, the channel "1" is selected and the channel number "1" is indicated by the leaf 8.

Besides, when the present channel is selected, the switch SW₃ is changed from the terminal a to the terminal b because of counterclockwise motion of the lever 18 and an operating voltage for the AFC circuit is imposed to the terminal c (FIG. 6).

Actual change-over of the tuning circuit involved in channel selection by the above-mentioned channel selecting mechanism is carried out by the mechanism shown in FIG. 5.

The mechanism shown in FIG. 5 is arranged to compose the tuning circuits corresponding to the preset channel number (20, for example), which is the maximum number of channels usually receivable in one area, out of the overall channel number (62, for example) contained in the above-mentioned channel selecting mechanism. To every contact in this mechanism, a resistance is connected beforehand for imposing the tuning voltage to the variable capacity element, which is connected to the tuning circuit in order to tune to each telecast channel in the receiving area.

Assuming that a sliding contact piece not illustrated is connected to the contact T_{m-2} which composes the tuning circuit for the channel "n-2" in the illustrated condition and the switch SW₁ is closed by pressing the button 21a in order to select the channel "1" from the channel "n-2" as described in the above, the following circuit is formed at the same time in addition to the abovementioned operation, i.e., the circuit from the

switch SW_2 — coil $42'$ of the electro-magnet 42 — diode D_2 — diode D_1 — to the switch SW_1 (or switch SW_2). So, the electro-magnet 42 is energized, the armature $42a$ is attracted and the feed pawl 44 is disengaged from the ratchet tooth R of the rotary shaft 41 (to the position shown by a dotted line). At that time, the shaft 41 tends to turn clockwise by the spring not shown. As, however, the shaft 41 is held by the resetting pawl $46b$ of the armature $46a$, the tuning circuit of the channel " $n-2$ " is still composed. After that, when the drum 12 passes through the position of the pin P_{n-1} which is not preset and stops at the position of the next preset channel selecting pin P_n , the switch SW_2 is opened at the same time, the above-mentioned operation circuit of the electro-magnet 42 is opened and said electro-magnet 42 releases the armature $42a$. Therefore, the feed pawl 44 mounted to the armature $42a$ engages with the ratchet tooth R on the shaft 41 and turns the shaft 41 counterclockwise by one tooth resisting the clockwise bias of the shaft 41 . Thus, the tuning circuit is changed over and telecast of the channel " n " is received.

When the button $21a$ is pushed again after the above, the same operation as described in the above is carried out and the drum 12 stops at the position of the next preset channel selecting pin P_1 , the tuning circuit is also changed over and the telecast of the channel " 1 " is received.

On the way during change-over from the channel " n " to the channel " 1 " (at the position of the hole h_0), the protuberance $12b$ provided at a portion on the periphery of the drum 12 engages with the switch SW_4 (position shown by a dotted line in FIG. 1) and closes said switch SW_4 . Consequently, the electromagnet 46 works and releases the pawl $46b$ of the armature $46a$, which was holding the shaft 41 from clockwise rotation, from the ratchet tooth R , thus said shaft 41 is quickly reset to the aforementioned reset position. Therefore, the tuning circuit is changed over in turn as described above being corresponding to pins P , which are preset successively, until the drum finishes its one rotation.

The setting and resetting mechanism for the above-mentioned channel selecting pins P on the drum 12 is shown in FIGS. 1, 2 and 4.

First, to reset said pins P , the button $24a$ of the second controlling lever 24 is to be pushed. That is, when said button $24a$ is pushed, the feed lever 27 is moved integrally by action of the spring 28 stretched with suitable tension and the drum 12 is turned by a predetermined angle by the feed pawl 29 mounted to said lever 27 . At that time, the position of said drum 12 is limited by the holding pin $16b$ provided to the armature $16a$ of the electro-magnet 16 . At the time when said drum 12 is turned by a predetermined angle, the stepped portion $27c$ of said feed lever 27 contacts the post 25 and said lever 27 is held at that position. When the button $24a$ is further pushed by resisting the spring 28 , only the second controlling lever 24 moves further and, by this movement, the stepped portion $24b$ of said lever 24 contacts the protuberance $32a$ of the resetting lever 32 to turn said lever 32 counterclockwise resisting the spring 36 (FIG. 4). Thus, the pin hammer 38 provided at the end of the lever 32 moves the pin P to the reset position (as shown by a two-dot chain line in FIG. 4).

On the other hand, said pin P at the reset position is moved to the set position by pushing the button $23a$ of

the first controlling lever 23 . That is, when said button $23a$ is pushed, the stepped portion $23b$ of said lever 23 contacts the protuberance $31a$ of the setting lever 31 , which turns clockwise resisting the spring 35 (FIG. 4). Therefore, the pin hammer 37 of said lever 31 moves the pin P from the reset position to the set position in the same way as described above.

The channel selecting pin P is held at the set or reset position as follows. That is, as it is evident from FIG. 2, the elastic belt 15 fitted in the annular groove $12a$ of the drum 12 fits in one of annular grooves g_1 and g_2 provided on the periphery of said pin P , i.e., said elastic belt 15 fits in said groove g_1 when said pin P is at the set position and in said groove g_2 when said pin P is at the reset position.

Besides, when rotation of the drum 12 is stopped as described in the above at the position where the channel selecting pin P is set, the stop lever 18 comes to the position shown by a full line in FIG. 1. At that time, the switch SW_3 connected as shown in FIG. 6 is changed over at the same time as the abovementioned operation and the connection of the movable contact of said switch SW_3 is changed over from the terminal a to terminal b . By this, a voltage is imposed to the terminal c to activate the AFC circuit which was inactive during rotation of the drum 12 . In the arrangement as described in the above, it is not always necessary to provide the hole h_0 at the working position of the drum 12 where the tuning circuit change-over mechanism is reset and the pin P_0 fitted in said hole h_0 .

Besides, it is also possible to integrally compose the stop lever 18 and locking lever 19 .

Instead of the afore-mentioned remote control switch SW_5 by wired connection, it is also possible to directly operate the switch SW_1 by radio control.

For the afore-mentioned switch mechanism 40 and switches SW_1 through SW_5 , it is also possible to adopt the non-contacting arrangement by using magnets and lead relays in combination.

The armature $16a$ of the electro-magnet 16 shown in FIG. 1 can be also held at the attracted position by electrically arranging a self-holding circuit of said electro-magnet 16 .

The feed pawl 29 is not always required to be normally engaged with the notches C of the drum 12 .

FIGS. 7 through 9 show another embodiment of the setting and resetting mechanism for the channel selecting pins P on the drum 12 involved in the above-mentioned embodiment of the present invention. In this embodiment, the switch SW_1 is arranged as a selector switch (FIG. 9), the lever 23 is provided with a resilient controlling member $23c$ for operating said switch SW_1 , thus the lever 27 and feed pawl 29 provided to the above-mentioned first embodiment are eliminated.

Operation of the mechanism shown in FIGS. 7 through 9 is as described below.

Assuming that FIG. 7 shows the condition when the channel " $n-1$ " is selected, the channel " 1 " will be selected from this condition as described below. In FIG. 1, every switch is at the position shown by a full line in FIG. 9 and the motor 2 and electro-magnet 16 are both in de-energized condition. When the button $21a$ of the channel controlling lever 21 is first pushed in the above condition, connection of the switch SW_1 is changed over (to the position shown by a dotted line in FIG. 9), the electro-magnet 16 is excited and its armature $16a$ is attracted and moves to the position shown by a dot-

ted line in FIG. 7. Therefore, the channel selecting drum 12 is disengaged from the holding pin 16b and, at the same time, the switch SW₂ is closed. At that time, however, the locking lever 19 is not engaged with the stop lever 18 and, therefore, said locking lever 19 is disengaged from the stepped portion 16c of the armature 16a because of the movement of said armature 16a to the position shown by a dotted line, turns counterclockwise to the position shown by the one-dot chain line in FIG. 7 and stops at that position. Thus, the armature 16a is held in the attracted condition by the locking lever 19 even when the button 21a is released and the switch SW₂ is held in the closed condition.

By resetting of the selector switch SW₁ caused by releasing of the button 21a in this condition, the switch SW₂ is changed over again and connected as shown by a full line in FIG. 9. So, the circuit of the motor 2 is closed and the motor 2 begins to rotate. Consequently, the channel selecting drum 12 turns being driven through the illustrated reduction gear mechanism. At that time, a ratchet stopper not shown here is suitably engaged with the notches C of said drum 12.

As said drum 12 rotates, the arm 18a of the lever 18 tends to engage with the pin P_n at the next position immediately. But, as said pin P_n is reset, the lever 18 does not work at that position at all. By the subsequent rotation of the drum 12, the stop lever 18 engages with the pin P₁ at the next position as said pin P₁ is in the set condition and said lever 18 is turned counterclockwise to the position shown by the dotted line. By this motion, the locking lever 19 is turned clockwise as its arm 19a is engaged with the arm 18b of the lever 18, thus the armature 16a locked by the end portion of the arm 19b is released. Consequently, the armature 16a tends to return to the position illustrated by the full line. At that time, the switch SW₁ is released and the holding pin 16b becomes engageable with the notches C of the drum 12. The drum 12 turns by inertia to some extent even when the circuit of the motor 2 is opened and then stops as the holding pin 16b completely engages with the notches C. At that time, the stop lever 18 drops to the position shown by the full line as its arm 18a is already disengaged from the pin P₁. Consequently, the locking lever 19 also becomes free and is turned counterclockwise by the spring 20. But, the counterclockwise turning is stopped halfway by the stepped portion 16c of the armature 16a and the lever is held at the position illustrated by the full line.

For the above-mentioned channel selecting mechanism, the program setting operation by pins P on the drum 12 for making said mechanism memorize the selecting positions is performed as follows.

When the button 23a of the first controlling lever 23 is pushed first, the switch operating member 23c changes the switch SW₁ over. Therefore, an operation same as in the above-mentioned case, where the button 21a of the channel controlling lever 21 is pushed, is carried out and the motor 2, in other word the drum 12, becomes ready to rotate. In this case, however, the actuating end 23b of the lever 23 works on the projecting end 31a of the setting lever 31 at the same time and turns said lever clockwise (FIG. 8) resisting the force of the spring 35. Consequently, the pin hammer 37 moves the pin P to the set position without fail. In this case, the pin P to be operated is the pin at the position just next to the position which corresponds to the channel selected (indicated) at that time. For example, if

the channel "n-1" is selected at present, the pin P_n at the position corresponding to the next channel "n" is set by the above operation. When the button 23a is then released the switch SW₁ is again changed over to its original position and, at the same time, the lever 31 also returns to its original position. Therefore, an operation same as the afore-mentioned case, where the lever 21 is released, is performed and the drum 12 rotates. In this case, however, the pin P at the next adjacent position is always set and the drum 12 always stops at said next adjacent position.

Therefore, judging whether the newly stopped position corresponds to the channel to be received, the button 24a of the second controlling lever 24 may be pressed again when it is not the necessary channel. Thus, the actuating end 24b of the lever 24 works on the engaging portion 32a of the presetting lever 32 to turn said lever 32 counterclockwise by resisting the force of the spring 36 and the pin hammer 38 resets the set pin P.

By repeating the above-mentioned operation, memory pins P of necessary channels are set. After that, the drum 12 is automatically stopped according to the set program of pins P only by pressing the channel controlling button 21a and the necessary channels are selected in turn.

The reason why the switch SW₁ is arranged as a selector switch in this embodiment is as described below. That is, in the former embodiment shown in FIGS. 1 through 6, the electro-magnet 16 is excited and the motor 2 is rotated at the same time when the switch SW₁ is closed. Therefore, the drum 12 continuously rotates as long as said switch SW₁ is kept closed and does not stop even when the pin P moves levers 18 and 19. This fact is advantageous when it is required to select the desired channel quickly. On the other hand, however, this arrangement has a disadvantage that, when it is desired to select the channel "n" after the channel "n-1," the drum 12 may pass the stopping position of the desired channel "n" unless the once closed switch SW₁ is opened immediately. To solve this problem, the switch SW₁ is composed as a selector switch in this embodiment and it is arranged so that the drum 12 stops without fail at the position of the preset channel selecting position. Of course the circuit shown in FIG. 9 can be also used for the mechanism shown in FIG. 1 only by changing the switch SW₁ for a selector switch.

We claim:

1. An angular position selecting and controlling device for a rotary member comprising:
a driving device,
a rotary member which rotates being interlocked with said driving device and can be stopped at every pre-determined rotary angle,
a stopping position limiting member which is movably attached to said rotary member in order to stop said rotary member at the position of the pre-determined rotary angle,
an electro-magnetic device having a pole-contacting member which is arranged adjacent to said rotary member and disengageably engages with said rotary member,
a first switch for opening and closing the energizing circuits of said driving device and said electro-magnetic device,
a second switch which is engageable with said pole-contacting member and which closes the operating

circuit of said driving device by means of said pole-contacting member when said pole-contacting member is attracted by said electro-magnetic device,

a stop lever member which is arranged adjacent to said stopping position limiting member and is engageable with said stopping position limiting member, and a locking lever member which is engaged with said stop lever member and is engageable with said pole-contacting member,

said angular position selecting and controlling device being arranged so as to retract said pole-contacting member from said rotary member by closing said first switch and to mechanically lock said pole-contacting member at the position where said pole-contacting member is attracted by said electro-magnetic device and, at the same time, to rotate said rotary member by closing said second switch by said pole-contacting member, and

said angular position selecting and controlling device being further arranged so as to subsequently release the mechanical locking of the above-mentioned pole-contacting member by means of engagement of the stopping position limiting member preset on said rotary member and said stop lever member and, at the same time, to open said second switch thereby making the pole-contacting member work on the rotary member and to thereat stop said rotary member.

2. An angular position selecting and controlling device for a rotary member according to claim 1, in which said device is provided with a selector switch as said first switch; said first switch being arranged so as to close said second switch by closing the operating circuit of said electro-magnetic device when said first switch is changed over to the first selecting position and, subsequently to close the operating circuit of said driving device when said first switch is changed over to the second selecting position.

3. An angular position selecting and controlling device for a rotary member according to claim 1, in which the device further comprises a group of change-over contacts each being arranged relative to said rotary member and being operable to compose circuits of a number smaller than the number of total angular positions in which said rotary member can be stopped, a contact change-over member supporting said group of contacts and being provided with ratchet teeth with a number of teeth corresponding to the number of contacts in said group of contacts, a first electro-magnetic device having a pole-contacting member which is arranged adjacent to said contact change-over member and being energized during the time when said rotary member is rotating, a feed pawl pivotably mounted to said pole-contacting member and capable of feeding

55

said contact change-over member by one pitch by engaging with said ratchet tooth when said first electro-magnetic device is de-energized, a second electro-magnetic device having a pole-contacting member which is arranged adjacent to said contact change-over member and engages with said ratchet tooth when said second electro-magnetic device is in de-energized condition, and a switch arranged adjacent to said rotary member and being closed to actuate said second electro-magnetic device when said rotary member completes its one rotation.

4. An angular position selecting and controlling device for a rotary member according to claim 1, in which the device further comprises a first operating member arranged at a position where said first operating member is engageable with said stopping position limiting member and, when being operated, moving said stopping position limiting member, which is at the reset position when said first operating member is to be operated, to the set position by engaging with said stopping position limiting member; a second operating member arranged at a position where said second operating member is engageable with said stopping position limiting member and, when being operated, said second operating member in the latter stage of its operating stroke moving said stop position limiting member, which is at the set position, to the reset position by engaging with said stopping position limiting member; and a third operating member connected to said second operating member and moving integrally with said second operating member in the first stage of the operating stroke of said second operating member in order to turn said rotary member by one pitch.

5. An angular position selecting and controlling device for a rotary member according to claim 1, in which the device further comprises a first operating member arranged at a position where said first operating member is engageable with said stopping position limiting member and, when being operated, setting said stopping position limiting member, which corresponds to the position next to the position selected at that time, by operating said first switch and energizing said electro-magnet, and at the same time, by opening the aforementioned driving circuit, and when said first operating member is returned to its original position, said first operating member being capable of closing said second switch; and a second operating member arranged at a position where said second operating member is engageable with said stopping position limiting member and, when being operated, said second operating member being capable of resetting said stopping position limiting member which corresponds to the above-mentioned position selected at that time.
